UNITED STATES PATENT OFFICE.

WILLIAM W. BLAKELY, OF DETROIT, MICHIGAN.

SECURING DEVICE FOR VEHICLES.

Application filed December 5, 1921. Serial No. 519,821.

This invention relates generally to devices for securing articles of merchandise to suitable supports and refers more particularly to devices for securing vehicles to the floor of a freight car or vessel, for safe shipment.

The invention consists in the structural features and arrangement of parts herein-after described, and illustrated in the accompanying drawing, wherein:

Figure 1 is a view in side elevation of the lower portion of a wheel, showing the improved securing device engaged therewith;

Figure 2 is a cross-section taken upon line 2—2 of Figure 1;

Figure 3 is an elevation of the device transverse to that of Figure 1;

Figure 4 is a top view of the wheel engag-

ing element.

In these views, the reference character 1 designates a wheel, the body of which is of the disk type, although the invention is equally applicable to any type of wheel.

Said invention comprises a tie member formed by arched rod or wire 2, a pair of attachment plates 3 carried by foot portions 4, formed terminally upon the legs of the arch 2, and a wheel engaging plate 5, mounted loosely upon the upper end of the arch 2. The plates 3 are each formed with a plurality of apertures 6, adapting said plates to be nailed to a floor such as is indicated at 7, and said plates are further formed

with centrally located slots 8 through which the foot portions 4 are loosely passed. Said foot portions are produced by terminally return-bending the legs of the arch 2 and spreading the adjacent strands of each foot

portion below the corresponding plate 3 to produce a loop 4^a, retaining said plate in assembled relation with the arch 2. Also the two strands of each foot member may be slightly diverged above the corresponding plate 3 to prevent said plate slipping up upon the leg of the arch and so disengaging from the foot portion thereof. It is preferred to similarly bend the loops 4^a at such an inclination to the legs of the arch 2 that they will lie flat beneath the plates 3, when the latter are secured to the floor 7, and will register with one of the nail holes 6. The plate 5 has the nature of a sheet metal stamping apertured as indicated at 9 for engagement with one of

the bolts 10, connecting the rim 11 of the wheel 1 to the body of said wheel, and having a hooked lower edge portion 11^a to engage the top of the arched tie member 2. The nut 12 on the bolt 10, which during shipment of a vehicle, holds the plate 5 in engagement with the wheel 1, is formed with a collar engaging within the opening 9 to protect the threads of the bolt. To secure said plate 5 loosely to the arch 2, openings 13 are formed in the bottom of the hooked portion 11^a adjacent the opposed edges thereof, tongues 14 being formed between each opening 13 and the adjacent edge, which tongues may be temporarily deflected from their positions closing the openings 13, to permit mounting of said plate upon the arch member.

It is a feature of the described invention that the plate 5 securing the tie member 2 to the wheel has considerable freedom of movement with respect to said tie member, permitting the secured vehicle to respond to shocks and vibration, incidental to travel, without unduly straining the floor fastenings of the arch member. Thus said plate may pivot upon the top portion of the tie member and may also move bodily to a limited extent either transversely to the tie member, or parallel thereto in either a horizontal or vertical direction. Thus slight movements of the vehicle in any direction are taken care of by the loose mounting of the plate 5 upon the tie member.

What I claim as my invention is:

1. In a vehicle securing device a tie member, means carried by one end thereof for securing said member to a floor, and a plate loosely mounted upon the other end thereof apertured to receive a bolt upon one of the vehicle wheels.

2. In a vehicle securing device, an arched tie member, comprising a top portion and leg portions, means carried by said leg portions for securing the tie member to a floor, and a plate loosely mounted upon the top of the tie member apertured for engagement by a bolt of a wheel of the vehicle to be secured.

3. In a vehicle securing device, an arched tie member, comprising a top portion and leg portions, means carried by said leg portions for securing the tie member to a floor, and a plate loosely mounted upon the top of the tie member having a hooked lower

portion, within which the top portion of the arch member is engaged, and apertured for engagement by a bolt of a wheel of the vehicle to be secured.

5. In a vehicle securing device, an arched tie member, comprising a top portion and leg portions, means carried by said leg portions for securing the tie member to a floor, and a plate loosely mounted upon the top 10 of the tie member having a hooked lower portion within which the top portion of the tie member is engaged, the bottom of the hook having openings adjacent its opposed edges to receive the tie member, the upper 15 portion of the plate being apertured for engagement by a bolt of a wheel of the vehicle to be secured.

5. The combination with an article of merchandise, and a support therefor, of 20 means for holding the article upon the support including a return bent tie member anchored upon the support, and a member secured to the article having an open hooked portion loosely connected to the return-bent 25 portion of the tie member aforesaid.

6. The combination with an article of merchandise, and a support therefor, of 25 means for holding the article upon the support including a tie member secured to the support, a headed element carried by the 30 article, a nut on the headed element, and a member connected to the tie member and

apertured to receive the headed element and a portion of the nut.

7. The combination with an article of 35 merchandise, and a support therefor, of means for holding the article upon the support including a tie member secured to the support, a bolt carried by the article, a plate connected to the tie member and apertured to receive the bolt, and a nut on the bolt having a projection in the plate for protecting the threads of the bolt.

8. The combination with an article of 45 merchandise, a support therefor, of means for holding the article upon the support including a tie member secured to the support, and a plate secured to the article having a hooked portion receiving a portion 50 of said tie member, and tongues projecting from the hooked portion toward the body portion of the plate for holding the portion of the tie member aforesaid in engagement with the hooked portion of said plate.

9. The combination with an article of 55 merchandise, and a support therefor, of an attaching plate secured to said article having a hooked portion provided with spaced 60 openings, and a tie member rigidly secured to said support having a loop portion engaging the openings in said plate.

In testimony whereof I affix my signature.

WILLIAM W. BLAKELY.
